CLAIM

The ornamental design for a coldness/heat preserving container, as shown and described.

DESCRIPTION

FIG. 1 is a perspective view of the coldness/heat preserving container showing my design;
 FIG. 2 is a front elevational view thereof, the rear view being identical thereto;
 FIG. 3 is a top plan view thereof, the bottom view being identical thereof;
 FIG. 4 is a right side view thereof;
 FIG. 5 is a left side view thereof;
 FIG. 6 is a cross-section taken across line A-A of FIG. 3; and,
 FIG. 7 is a cross-section taken across line B-B of FIG. 3.
